UNITED STATES PATENT OFFICE.

ARTHUR C. BUNKER, OF MONTCLAIR, NEW JERSEY, ASSIGNOR TO CROCKER-WHEELER ELECTRIC MANUFACTURING COMPANY, OF AMPERE, NEW JERSEY, A CORPORATION OF NEW JERSEY.

MOTOR-STARTING SWITCH.

Application filed January 28, 1924. Serial No. 689,121.

One object of this invention is to provide a switch for electric motors which will control heavy currents, and will automatically function so that the requisite interval will elapse between the effecting of starting and running connections after the starting of the switch movement has been initiated. Another object is to provide a switch which can be used where dust or inflammable vapors are present without danger of explosion. A further object is to provide a switch in which opening and exposure of the switch contacts while current is flowing therethrough is automatically prevented. A further object is to provide a switch of compact and rugged construction.

In the accompanying two sheets of drawings which form a part of this specification, Figure 1 is a front view of the switch in off position, the cover being removed, the tank being lowered, and the tank and dashpot being shown in section.

Fig. 2 is a section on the line II—II of Fig. 1.

Fig. 3 is a rear view of the main switch member.

Fig. 4 is a diagram of the circuits. A case 5 with a cover 6 encloses suitable actuating mechanism. Its lower side is a slab of insulating material as wood or slate, against which a tank 7 for oil is held and in which the main switch contacts are made and broken. The tank has a lip 8 which is engaged by the cover of the case and the tank is locked in place thereby. Rods 9, 9 depend from the case and nuts 10, 10 on the lower ends of the rods engage under slotted ears 11, 11 on the sides of the tank near the bottom. The rods also pass through holes in ears 12, 12 on the sides of the tank at the top. It is therefore only necessary to remove the cover and slacken the nuts to slide them out of engagement with the slotted ears and lower the tank to the position shown in which oil which temporarily adheres to the switch parts can drain into the tank, but to remove the tank for emptying and cleaning, the nuts must be removed since the upper ears are not slotted.

The switch as shown is for effecting the proper connections between three line leads L₁, L₂, L₃, at fingers 13, 14, 15 and three motor leads M₁, M₂, M₃, either directly at fingers 16, 17, 18, or through fingers 19, 20 attached to the ends of an auto-transformer 21, and through fingers 22, 23 attached to the ends of an auto-transformer 24. The connections are made in different ways for starting and for running. The switch therefore has in addition to a running position at least one starting position. The invention is not limited to any particular arrangement of connections between the line leads, the leads of the instrumentalities, as the auto-transformers, which are used in starting, and the motor leads.

The fingers are shown in the diagrammatic figure in a single row for convenience in illustrating the circuits, but they are preferably disposed in two opposed horizontal rows, one behind the other on the same level and the rear row including the fingers which are directly connected to the line leads so that when the switch is open all of the more accessible parts will be dead. The connections are made for starting and running by suitably interconnecting the fingers by three contact sections 25, 26, 27 on the two sides of a main switch member the lower part of which is in the form of a wooden board 28. Each of the contact sections is an inverted U-shaped piece, its two branches lying on the two sides of the board and its connecting part lying in a mortise in the top edge of the board. A wooden cap-piece 29 is screwed to the top edge of the board which carries the contact sections and the fingers bear against the two sides of this when the switch is open. The proper connections are made, first for starting and then for running, by lifting the main switch member so as to bring first the contacts in the upper rows on the two sides into contact with the fingers, and finally the contacts in the lower rows into contact with the fingers. Springs 30, 30 drop the main switch member to the open position shown when it is not supported.

A lifting rod 31 is attached to the switch

member and extends upwardly through the bottom of the case into the case. In the case is a solenoid 32 with an armature 33 which carries pawls 34, 34 arranged to engage with notches 35, 35 in the two edges of the lifting rod. The stroke of the solenoid armature is slightly greater than the distance which the main switch member is moved in going from the open position to the starting position or in going from the starting position to the running position. Current is supplied to the solenoid for the initial stroke in lifting the main switch member to the starting position by closing a starting switch 36. The circuit is then from one of the line leads through a lead 37, the starting switch, through a lead 38, a contact spring 39 to a pilot switch member 40 in which the pilot switch member is connected permanently through a flexible lead 41 to the solenoid. Thence the circuit is through a lead 42 to another line lead.

When the main switch is lifted to the first position a pin 43 on the lifting rod is removed from engagement with a lever 44 which is actuated by a spring 45. This spring is not of sufficient strength to interfere with the dropping of the main switch member. The lever having been released, it lifts through a latch 46, a piston rod 47 which carries the pilot switch and also a piston 48 of a dash-pot 49. The dash-pot is preferably filled with oil to a sufficient height to cover the pilot switch in order to reduce the hazard in case the switch is where the atmosphere may be explosive from the presence of dust or vapor. There are openings through the piston to permit the escape of oil from one side to the other. These are partially closed by a valve 50 past which the oil can leak slowly so that the spring actuated lever will slowly lift the pilot switch. As the switch rises an insulating collar 51 breaks the circuit through the solenoid and lets its armature fall.

In the meantime the motor-leads have received current and a circuit has been established from one of the motor-leads through a lead 52, a stopping switch 53, a lead 54, a no-voltage release magnet 55, a lead 56, a safety switch 57, and a lead 58 to a terminal of one of the auto-transformers which is connected to one of the line leads through the main switch. A roller 59 on an arm of the no-voltage release magnet armature engages a notch 60 on the lift rod and prevents the main switch from falling back with the armature of the solenoid.

After a sufficient interval of time for the motor to start and speed up so that final running connections may be made, the pilot switch will near the upper limit of its travel and the circuit through the solenoid will be again established through that portion of the pilot switch which is below the

insulating collar. If in the meantime the operator has opened the starting switch, there will be a second path for current through a lead 61 and a contact spring 62, so that the switch having started to close will go to full running position whether or not the starting switch is momentarily closed or is held closed.

On the second operation of the solenoid the pawls carried by its armature engage notches 63, 63 in the lift rod and the main switch member is brought to the position for establishing the final running connections. It is retained in this position by the engagement of a notch 64 in the lift rod by the roller on the arm of the no-voltage release magnet armature. As the spring-actuated lever nears the upper limit of its movement the tail of the latch which is carried by it will engage a pin and the piston rod will be released and will fall, but it will only fall part way when it will be stopped by a pin 66 carried by the piston rod striking the top of the spring actuated lever which is in the position shown in dotted lines. This shifts the pilot switch so that all connections through it are broken and the solenoid has no current while the main switch continues in the running position and no circuit can be made through the starting switch until the main switch has gone back to its open position and the spring actuated lever has been engaged by the pin on the lift rod and brought down to the position shown.

The main switch is returned to open position by opening the stopping switch which breaks the circuit through the no-voltage release magnet and lets the main switch member fall.

Should the cover to the case be removed while contacts are made, the removal of the cover will release the safety switch and the main switch will at once drop to the open position and cannot be operated from the starting switch until the safety switch has been closed by putting back the cover. Also as it is necessary to remove the cover before the tank is released, it follows that the contacts in it cannot be exposed while current is flowing.

I claim—

1. In a motor starting switch, means for establishing motor starting connections, means for establishing motor running connections, an actuating magnet, a circuit therefor, a reciprocating armature therefor, means for coupling the reciprocating armature to the means for establishing motor starting connections, a pilot switch with delayed movement for opening and reclosing the circuit for the actuating magnet after motor starting connections are established to effect a second reciprocation of the actuating magnet, and means for coupling the reciprocating armature to the means for establish-

ing motor running connections on the second reciprocation of the actuating magnet.

2. A motor starting switch, actuating mechanism therefor, an oil-tank in which the switch is submerged, a case for the actuating mechanism provided with a cover, means connected with the cover for locking the oil-

tank in position, a no-voltage release magnet for retaining the switch in actuated position, and a safety switch in the circuit of the no-voltage release magnet which is held closed by the cover of the case. ¹⁰

ARTHUR C. BUNKER.
